UNITED STATES PATENT OFFICE

2,612,849

HATCH CONSTRUCTION FOR RAILWAY CARS

John S. Lundvall, Park Ridge, Ill., assignor to
Union Asbestos & Rubber Company, Chicago,
Ill., a corporation of Illinois

Application May 27, 1949, Serial No. 95,705

9 Claims. (Cl. 105—377)

1

This invention relates to a hatch construction for railway cars and more particularly to the construction of hatches in refrigerator cars.

It has heretofore been the customary practice in the construction of refrigerated railway cars to form hatch openings adjacent the ends of the car between carlines extending from one side of the car to the other. One construction of this type is shown, for example, in the patent to Bon-sall, No. 2,037,115. Such constructions including carlines are relatively expensive and are difficult to install since they must be built into the car at the time the car is constructed. Furthermore, this construction provides a continuous metal heat conduction path from the interior to the exterior of the car around the hatch opening.

It is one of the objects of the present invention to provide a hatch construction in which the necessity for carlines or other relatively expensive supports is eliminated.

Another object is to provide a hatch construction which is directly supported by the side and end walls of the car and by a beam extending across the car spaced from the end wall. According to one important feature of the invention, the beam may be formed by a header at the top of a bulkhead in the car or by a separate strip attached to the header so that the bulkhead contributes substantially to the support of the hatch construction.

Still another object is to provide a hatch construction which can easily be assembled in or disassembled from a car after the remainder of the car is completed.

A further object is to provide a hatch construction in which an inner supporting plate or sheet serves as a ceiling for the ice compartment of the car.

A still further object is to provide a hatch construction in which both the inner and outer edges of the hatch opening are metal lined, but the metal is interrupted in the central portion of the opening to interrupt the heat conducting path. In one desirable construction the outer lining is formed by an inwardly turned flange on the roof sheet of the car.

The above and other objects and advantages of the invention will be more readily apparent when read in connection with the accompanying drawings, in which—

Figure 1 is a partial longitudinal section with parts in elevation of a refrigerator car embodying the invention;

Figure 2 is a transverse section on the line 2—2 of Figure 1; and

Figure 3 is a top plan view of the supporting

plate or sheet partially illustrating the fastening mechanism for the frame.

The invention is illustrated in connection with a more or less conventional refrigerator car having insulated side walls 10, an insulated end wall 11 covered with a corrugated metal sheet 12 terminating at its upper edge in a horizontal flange 13, and an insulated roof 14. The roof is covered with metal roof sheets 15 connected at their abutting edges by flanged connections 16 and the end most roof sheet 17 being formed over and secured to the flange 13. The sheet 17 is formed with a pair of laterally spaced openings therethrough registering with edge openings in the top of the car and which are defined by inwardly turned tapering flanges 18.

Within the car, as shown, there is a transverse bulkhead 19 formed by upwardly extending beams 21 covered throughout a portion of their height by a cover 22 of planks or the like. At their upper ends the beams are connected to a header 23 formed by flanged plates fitting together back to back with the flanges thereof fitting over and secured to the top ends of the beams. At their upper edges the plates are turned over as indicated at 24 to underlie the roof of the car and to assist in supporting it. At their opposite ends the plates forming the header are provided with outwardly extending flanges 25 which fit against and are secured to the sides of the car by means of lag screws or the like.

The car construction as so far defined may be completed before installation of the hatch construction of the present invention which may be completely fabricated apart from the car and installed therein at any convenient time. As shown, the hatch construction of the invention comprises a supporting plate or sheet 26 which is preferably formed of relatively heavy gauge sheetmetal and which has an opening 27 in its central portion. The opening is defined by an upwardly extending flange 28 which flares outward at its upper edge at the same angle as the flange 18 so that when the parts are assembled the flanges 18 and 28 will lie in alignment. At its periphery the plate or sheet 26 has its edges turned down to form flanges 29 throughout its entire periphery. The flanges 29 serve both to strengthen the sheet and as a mounting means therefor as will appear more fully hereinafter. As best seen in Figure 2, the flanges 29 at the front and rear edges of the sheet are tapered to the same degree as the slope of the roof at the sides of the car, being deeper toward the center of the car than toward its sides.

Around the flange 28 there is mounted a frame preferably formed of non-metallic material such as wood. As shown, the frame is formed by four straight pieces of wood 31 which lie, respectively, against the four sides of the flange 28 and which are shaped to fit against the flange. At their upper edges the strips 31 are shaped to interfit with the flange 18 when the parts are assembled. The strips 31 may be held in place in any convenient manner and, as shown, are secured around the flange 28 by means of a pair of U-shaped metal straps 32 which are turned outwardly at their ends, as shown at 33, and held together by bolts 34. Due to the flare of the flange 28 and the complementary shape of the strips 31, the strips will be held securely in place on the flange once the straps 32 are tightened around them.

With the strips 31 assembled on the plate or sheet 26, it may be mounted in the car simply by raising it from the interior of the car into assembled position in the hatch opening. As the assembly is raised the upper edges of the strips 31 will engage the flanges 18 and the undersurfaces of the roof sheet 17, as shown. It will be noted that in this position the edges of the flanges 18 and 28 are separated so that there is an interruption in the metal heat conducting path from the interior to the exterior of the car. To provide a smooth surface on the interior of the hatch opening, the strips 31 are formed with ridges 35 projecting therefrom and of a size to fill the space between the flanges.

For mounting the hatch construction in the car, it is necessary only to raise the plate 26 and frame 31 upward into the position shown from the interior of the car. When in position, the flanges 29 on the plate will lie against the car end wall at one side of the plate and the car side wall at an adjacent side of the plate. The forward flange will lie against an angle strip 36 which is secured to the top of the header over the bulkhead. The flanges at the end and side walls of the car are secured thereto by lag screws 37 or the like to fasten the plate 26 securely in the car. The flange at the forward edge is bolted to the angle strip 36 by bolts 38 securely to support the forward edge of the plate. It will be noted that the strip 36 may be relatively light since the major part of the strength required is furnished by the header and by the bulkhead itself. Each of the plates 26 is of approximately half the width of the car, as seen in Figure 2, and two plates are mounted in side by side relationship to fill the full width of the car. When so assembled, the flanges on the plates adjacent to the center of the car abut each other and are connected by means of bolts 39. In this way both of the hatch constructions are securely and rigidly supported in the car without requiring any complicated or expensive carline structures as heretofore required.

If it should become necessary at any time to remove the hatch construction, this can easily be done simply by removing the screws 37 and the bolts 38 and 39 and dropping the entire hatch construction into the car interior. Thereafter the hatch construction may be repaired and replaced. All repair operations on the remainder of the car adjacent its end may be accomplished without requiring dismantling of any other portions of the car.

To close the hatch opening, the usual insulated closure or plug 41 is provided having a peripheral flange 42 which overlies the peripheral portion of the flange 18. A sealing ring 43 of resilient

sealing material may be carried by the flange 42 to seal it securely against the flange 18, and if desired, the body of the plug may have a relatively tight fit against the flanges 18 and 28 and the separating ridge 35.

While one embodiment of the invention has been shown and described in detail herein, it will be understood that this is illustrative only and is not to be taken as a definition of the scope of the invention, reference being had for this purpose to the appended claims.

What is claimed is:

1. A hatch construction for a railway car comprising a non-metallic frame formed with a tapered opening therethrough, an outer metal cover sheet formed with a downwardly tapered flange extending into the frame opening in contact with the inner tapered wall thereof and terminating intermediate the upper and lower edges of the opening, and an inner metal cover sheet having an upwardly flaring flange extending into the frame opening in contact with the inner tapered wall thereof and terminating in spaced relation to the flange on the outer cover sheet, said flanges being aligned and forming a tapered surface to receive a tapered closure member, said non-metallic frame having an inwardly projecting ridge in its central portion lying between the flanges and forming with the flanges a substantially smooth surface.

2. In a railway car having top, end and side walls, a hatch construction comprising a metal supporting plate mounted adjacent the car end wall and formed with a central opening therein, an upwardly extending flange around the opening, a non-metallic frame supported on the plate around the flange, a beam extending across the car parallel to and spaced from its end wall, and means securing the plate to the car end and side walls and to the beam.

3. In a railway car having top, end and side walls, a hatch construction comprising a metal supporting plate mounted adjacent the car end wall and formed with a central opening therein, an upwardly extending flange around the opening, a non-metallic frame supported on the plate around the flange, a beam extending across the car parallel to and spaced from its end wall, and downwardly turned flanges at the periphery of the sheet engaging and secured to the end and side walls of the car and the beam.

4. In a railway car having top, end and side walls, a hatch construction comprising a metal supporting plate mounted adjacent the car end wall and formed with a central opening therein, an upwardly extending flange around the opening, a non-metallic frame supported on the plate around the flange, a beam extending across the car parallel to and spaced from its end wall, means securing the plate to the car end and side walls and to the beam, and a roof sheet on the car having an opening therein registering with the frame and defined by a downwardly turned flange fitting into the frame.

5. In a railway car having top, end and side walls and formed with a pair of hatch openings in its top adjacent its end, a hatch construction comprising a pair of metal supporting plates lying side by side adjacent the car end and together spanning the full width of the car, each of the plates having a central opening therein registering with one of the hatch openings and defined by an upwardly extending flange, a non-metallic frame fitting around each flange, a beam extending across the car parallel to and spaced from

the end wall and engaging the edges of the plates, and means for connecting the edges of the plates to the car end and side walls and the beam, and to each other where they abut adjacent the center line of the car.

6. In a railway car having top, end and side walls formed with a pair of hatch openings in its top adjacent its end, a hatch construction comprising a pair of metal supporting plates lying side by side adjacent the car end and together spanning the full width of the car, each of the plates having a central opening therein registering with one of the hatch openings and defined by an upwardly extending flange, a non-metallic frame fitting around each flange, a beam extending across the car parallel to and spaced from the end wall and engaging the edges of the plates, and downwardly turned flanges at the edges of the plate overlying and secured to the end and side walls of the car and the beam and with flanges on the two plates engaging and secured together adjacent to the center of the car.

7. In a railway car having top, end and side walls and formed with a pair of hatch openings in its top adjacent its end, a hatch construction comprising a pair of metal supporting plates lying side by side adjacent the car end and together spanning the full width of the car, each of the plates having a central opening therein registering with one of the hatch openings and defined by an upwardly extending flange, a non-metallic frame fitting around each flange, a beam extending across the car parallel to and spaced from the end wall and engaging the edges of the plates, and means for connecting the edges of the plates to the car end and side walls and the beam, and to each other where they abut adjacent the center line of the car, and a metal cover sheet over the top of the car formed with openings register-

ing with the hatch openings and having downwardly extending flanges projecting into the frames.

5 8. In a railway car having end and side walls, a top and a bulkhead extending across the car spaced from its end, a beam extending across the car at the top of the car and supported at least in part by the bulkhead, a supporting plate extending between the end wall of the car and the beam at one side of the car and formed with a central opening, an upwardly extending flange around the opening, a frame supported by the plate around the flange, and means securing the edge portions of the plate to the car end and side walls and the beam.

10 9. In a railway car having end and side walls, a top and a bulkhead extending across the car spaced from its end, a beam extending across the car at the top of the car and supported at least in part by the bulkhead, a supporting plate extending between the end wall of the car and the beam at one side of the car and formed with a central opening, an upwardly extending flange around the opening, a frame supported by the plate around the flange, and a downwardly turned flange at the edges of the plate fitting against and secured to the car end and side walls and the beam.
